UNITED STATES PATENT OFFICE.

FREDERICK HANDLEY PAGE, OF LONDON, ENGLAND, ASSIGNOR TO HANDLEY PAGE LIMITED, OF LONDON, ENGLAND.

MEANS FOR BALANCING AND REGULATING THE LIFT OF AIRCRAFT.

1,422,616.

Specification of Letters Patent.

Patented July 11, 1922.

Application filed December 6, 1921. Serial No. 520,422.

To all whom it may concern:

Be it known that I, FREDERICK HANDLEY PAGE, a subject of the King of Great Britain, residing at London, England, have invented certain new and useful Improvements in Means for Balancing and Regulating the Lift of Aircraft, of which the following is a specification.

In order to vary the relative lift of the wings on the port and starboard sides of an aeroplane flying machine to maintain the lateral stability of said machine about the axis of flight, or to cause the lift of both wings on opposite sides of said machine to be increased, flaps or ailerons, hereinafter termed flaps, are usually provided, being hinged adjacent their forward edges to the rear edges of the wings, and which flaps can be increased in angle or turned downwards as required by means operable by the pilot, and which means are so well known as not to call for description in this specification, and the object of the present invention is to provide means, as hereinafter described and claimed, by which the effect produced by such hinged flaps is greatly increased.

I have ascertained, as the result of numerous experiments, that by the wing having a slot or slots through the wing structure from the under surface to the upper surface and extending in length transversely to the line of flight, the lift of such a wing can be increased by admitting air from the under side to the upper side of the wing surface by way of said slot or slots, and when the wing is flown at large angles of incidence the lifting effect is considerably increased. As a further result of experiments I have found that the openings of the slots on the under surface of the wing structure should preferably be larger and more forwardly located than the openings on the upper surface.

Now the present invention consists in utilizing and adapting the above mentioned method of increasing the lift, to augment the lifting effect produced by wing flaps when the latter are increased in angle or receive a downward movement about their hinges.

According to the present invention each flap, which is carried by a pivot pin or equivalent hinge member supported from the rear part of the wing, is formed or con-

structed with a through slot extending transversely of the line of flight and permitting of the passage of air from the under surface of the wing structure to the upper surface of the flap, and means are provided to effect the closure of the said slot when the flap is in its normal or in its raised positions, and to open the said slot when the flap is increased in angle by being given a downward movement about its pivot or hinge member. Preferably the slot extending from the under surface to the upper surface of the flap is larger on the under surface than on the upper surface of said flap, and the walls of said slot are preferably curved rearwardly from the lower surface to the upper surface.

The invention will be further described with reference to the accompanying drawings which sufficiently illustrate the rear portion of a wing with a hinged flap coacting therewith, the said drawings illustrating two constructions. Figs. 1 and 2 show respectively the flap in its normal position and the flap turned upwards, in both of which positions the slot through the flap is closed, while Fig. 3 shows the flap turned downwards, in which position the said slot through the flap is open.

Figs. 4, 5 and 6 are views corresponding to Figs. 1, 2 and 3, but showing an alternative means of maintaining the closure of the slot through the flap when in its normal and upturned positions, and automatically opening said slot when the flap is turned downwards.

Referring to Figs. 1, 2 and 3 of the drawings, 1 represents the rear portion of an aeroplane wing, 2 representing the rear spar of the wing. The wing flap 3 is hinged or pivoted near its forward end to the wing structure by a hinge member of any suitable construction, and as indicated in the drawings, the flap 3 is hinged at 4, the hinge member being supported from the rear spar 2 of the wing 1.

Adjacent its leading end, the wing flap 3 is formed with a slot 5 extending from the under surface to the upper surface of said flap, and said slot 5 extends in length transversely to the line of flight. A preferable construction of the slot is shown on the drawings, in which the opening on the under surface of the wing flap 3 is larger than the opening on the upper surface, and

the walls of the slot are curved in a rearward direction from its opening on the under surface to its opening on the upper surface of the flap 3.

- 5 According to this invention means are then provided to effect the closure of the said slot when the flap is in its normal position as at Fig. 1, or in its raised position as at Fig. 2, and to open the said slot 10 5 when the flap is increased in angle by being brought into the position as at Fig. 3 where it has received a downward movement about its hinge member 4. To effect this in the construction shown at Figs. 1 15 to 3 a shutter 6 consisting of a plate of any suitable material is permanently fixed by screws or other means at its forward end at 7 to the wing structure 1, the said shutter extending rearward over the upper surface 20 of the flap 3 for such a distance as to close the mouth of the slot 5 on the upper surface of the flap 3 when the latter is in either of the positions shown at Figs. 1 and 2.
- 25 Means are provided for retaining the shutter 6 in surface contact with the wing flap 3, and in the example shown the shutter is slotted and a headed pin 8 passes through the slot and is fixed to the wing flap 3 so that 30 when the wing flap 3 is moved about its hinges the pin 8 will be drawn along the slot of the shutter 6.

When however the wing flap 3 is turned downwards about its hinges 4, it will be observed that the slot 5 is opened, the mouth on the upper surface of the flap being located at that time beyond the rearward edge of the shutter 6.

Referring to the construction shown at 40 Figs. 4, 5 and 6, the mouth of the slot 5 on the upper surface of the wing flap 3 is closed, as at Figs. 4 and 5, by a shutter 9 hinged at 10 to the rearward wall of the slot 5 of the wing flap, while the forward end of the 45 shutter 9 is in contact with the forward wall of the slot 5 in the flap 3, and an arm 11 is fixed to the axis of the shutter 9, which arm projects upwards and is drawn rearwards by a spring 12 fixed to the arm at one end 50 and to the flap 3 at the other end, so that until the arm 11 is acted upon, the shutter 9 is closed and prevents air passing from the under surface to the upper surface of the flap 3.

55 Pivoted at 13 to the spar 2 of the wing 1 is one end of a link 14, the rearward end of which is formed with a slot 15 which engages a pin on the end of the arm 11, and the slot is such that the link 14 does not act 60 upon the arm 11 in either of the positions shown at Figs. 4 and 5, that is it does not act on the arm 11 when the wing flap is in the normal position as at Fig. 4, nor does it act on the arm 11 when the flap is in the 65 upward position shown at Fig. 5, and conse-

quently in both of these positions the shutter 9 is held closed by the air pressure beneath the surface of the wing structure and by the action of the spring 12.

When however the flap 3 is turned downwards about its hinge 4, as shown at Fig. 6, the pin on the arm 11 which has reached the rear end of the slot 15 of the link 14, is acted upon, and the shutter 9 is rocked about its hinge 10 into a recess provided for it in 70 the rear wall of the slot 5, and thus the slot 5 is open when the wing flap 3 is turned downwards, and air passes from the under surface to the upper surface of the wing flap 3.

80 It will readily be seen from the above description that when the flap is drawn down for the purpose of increasing its angle and therefore increasing the lift on that wing to which it is attached, the increase in lift is 85 augmented for the reason that not only is the lift secured due to the angle given to the flap, but additional lift is gained due to the air passing through the slot maintaining the suction effect over the flap in spite of the 90 considerable angle imparted to the flap.

What I claim as my invention and desire to secure by Letters Patent is:—

1. In laterally balancing or regulating the lift of the wings of aeroplane flying machines, the combination of flaps located at the rear edges of said wings, hinge members located adjacent the forward end of each flap and connected to the main wing structure to pivotally support said flap, said flap having a slot extending from the under surface and adjacent the forward end of said flap to the upper surface of said flap, said slot extending in length transversely to the line of flight, and means in operative connection with the main wing structure to open said slot in said flap when the latter is turned into its downward position to admit of the passage of air through said slot from the under surface to the upper surface of said flap and to close said slot when said wing flap is in its normal or raised positions.

2. In laterally balancing or regulating the lift of the wings of aeroplane flying machines; the combination of flaps located at the rear edges of said wings, hinge members located adjacent the forward end of each flap and connected to the main wing structure to pivotally support said flap, said flap having a slot extending from the under surface and adjacent the forward end of said flap to the upper surface of said flap, said slot extending in length transversely to the line of flight, a shutter carried by said flap to open or close said slot in said wing flap, and means 120 to connect said shutter to the main wing structure to open said shutter carried by said flap when the latter is turned into its downward position to admit of the passage of air through said slot from the under surface to 125 the upper surface of said flap, and to close said slot when the flap is turned into its upward position.

the upper surface of said flap and to close said slot by said shutter when said wing flap is in its normal or raised position.

3. In laterally balancing or regulating the lift of the wings of aeroplane flying machines; the combination of flaps located at the rear edges of said wings, hinge members located adjacent the forward end of each flap and connected to the main wing structure 5 to pivotally support said flap, said flap having a slot extending from the under surface adjacent the forward end of said flap to the upper surface, the opening of said slot on the under surface of said flap being larger 10 than the opening on the upper surface, and the walls of said slot being curved rearwardly from the lower surface to the upper surface, and means in operative connection with the main wing structure to open said 15 slot in said flap when the latter is turned into its downward position to admit of the passage of air through the said slot from the under surface to the upper surface of said flap and to close said slot when said wing 20 flap is in its normal or raised positions.

4. In laterally balancing or regulating the lift of the wings of aeroplane flying machines; the combination of flaps located at the rear edges of said wings, hinge members 25 located adjacent the forward end of each

flap and connected to the main wing structure to pivotally support said flap, said flap having a slot extending from the under surface and adjacent the forward end of said flap to the upper surface of said flap, said 30 slot extending in length transversely to the line of flight, a shutter comprising a plate fixed at its forward end to the upper rear surface of the main wing structure and extending rearwards over the upper surface of 35 said flap, and means for retaining said plate in contact with the upper surface of said flap while permitting of movement of the latter relatively to said plate, said plate composing said shutter extending rearward over the 40 surface of said flap for such a distance as to close said slot through said flap by said shutter when said flap is in its normal or raised position, and to leave said slot of said flap open when said flap is turned into its down- 45 ward position to permit of the passage of air through said slot from the under surface to the upper surface of said flap. 50

In witness whereof I have hereunto set my hand in the presence of two witnesses.

FREDERICK HANDLEY PAGE.
